(57) **CLAIM**

The ornamental design for a display screen with animated icon, as shown and described.

DESCRIPTION

FIG. 1 is a front view of a first image in a sequence of a display screen with animated icon, showing the new design; FIG. 2 is a second image thereof; and, FIG. 3 is a third image thereof.

The appearance of the image transitions sequentially between the images shown in FIGS. 1-3. The process or period in which an image transitions to another image forms no part of the claimed design.

The broken lines of uneven length show the display screen and form no part of the claimed design. The broken lines of even length shown in the drawing illustrate portions of the display screen with animated icon that form no part of the claimed design.
